OUTLET BOX ATTACHING MEANS

Gerhard P. Schwabacher, Bridgeport, Conn., as-
signor to General Electric Company, a corpora-
tion of New York

Application December 29, 1933, Serial No. 704,495

10 Claims. (Cl. 247—21)

This invention relates generally to switch boxes and is directed more particularly to the means secured to said boxes for attaching them to building structures.

5 It is an object of the present invention to provide attaching members which are secured to a switch box but are adjustable either to a position lying in the same plane as the upper edge of the box or to a position offset from the edge of the

10 box.

In carrying out this object the attaching members are each provided with two ears rotatably pivoted to a wall of the box. By rotating the ears to a position lying in the same plane as the 15 edge of the box, the ears are caused to abut against, and to align with, one another to form an attaching member in the same plane as the edge of the box. By rotating the ears to a position offset from the edge of the box the ears are 20 caused to abut against and to align with one another to form an attaching member offset from the edge of the box.

Other objects of the invention will be apparent upon reference to the following detailed description and to the drawing in which Fig. 1 illustrates a switch box with the attaching member offset from the edge of the box; Fig. 2 illustrates the attaching member in the same plane as the outer edge of the box; and Fig. 3 shows the manner 25 of attaching the ears to a wall of the box.

Referring now to the drawing, the body of the switch box may be of any common or suitable form having the usual bottom (not shown), side walls 1 and end walls 2 which in this case are rectangular. The end wall 2 is provided with the usual knockout openings 3 for the introduction of electric conduits (not shown). Extending outwardly from the upper edge 4 of the end wall 2 is a lug 5 provided with a threaded hole 6 affording 35 means for attaching to the end wall of the box a wiring device (not shown) positioned within the box.

Two ears 7 and 8 secured to each end wall 2 cooperate to form the attaching member which is 40 adjustable to the two positions mentioned above. Each ear is formed from a blank having a first portion provided with an opening 9 and an arm 10 and a second portion substantially perpendicular to the first portion and provided with an 45 opening 11 and with the oppositely disposed arms 12 and 13. Each ear 7 and 8 is rotatably pivoted to the end walls 2 by swedging part of the ear through an opening 14 of the end wall and spinning this part over on the inside of the wall 50 as shown at 15 in Fig. 3.

When it is desired to have the attaching member offset from the upper edge 4 of the end wall 2, the ears 7 and 8 are rotated in opposite directions to the position shown in Fig. 1. In this position the arms 10 and 13 of the ear 7 abut against, or bear upon, the arms 10 and 13 of the ear 8. The second portions of the ears are accordingly aligned to form an attaching member offset from the upper edge of the box while the abutting arms 10 and 13 prevent any undesired movement of the 55 aligned ears. By means of the openings 11 in the aligned ears 7 and 8 the switch box can then be secured to the wall structure, with its upper portion offset from the wall.

A wiring device (not shown) is disposed within the box and mounted upon the end walls 2. In order to have the face of this device flush with the wall surface it is sometimes necessary to raise it slightly by means of supports which rest on the plaster surface or by mounting it on washers disposed on the lugs 5. The screws or bolts (not shown) which serve to fasten the wiring device to the lugs 5 must accordingly be made of sufficient length to permit the device to be raised in the manner mentioned. To permit the screws 70 or bolts from striking against the attaching member when the wiring device is not thus raised, the ears are designed to form an opening 16 when they are in the position shown in Fig. 1.

When it is desired to have the attaching member in the same plane as the upper edge 4 of the end wall 2, the ears 7 and 8 are rotated relatively to one another in opposite directions and counter to their first direction of rotation to the position in Fig. 2. This position is 180° distant from the 85 position of the attaching member shown in Fig. 1. In this position the arms 12 of each ear abut or bear upon one another and these arms are so designed that they then provide an opening enclosing the lug 5. The second portions of the ears are again aligned to form the desired 90 attaching member while the abutting arms 12 prevent any undesired movement of the aligned ears. As previously stated the openings 11 in the aligned ears afford means for securing the 95 switch box to the wall structure but in this case the box is attached to the wall structure with its upper edge in the same plane as the wall surface.

The invention provides a novel means for adjusting the attaching member of a switch box or other receptacle to the two positions required by the conditions met with when installing such boxes. By providing the adjustable supporting member with two separate ears rotatably piv- 105

55 110

oted to the end wall, the supporting member can be adjusted to either of the two required positions by a simple rotation of each of the ears. At the same time the abutting arms of 5 the ears prevent any undesired movement on the part of the aligned ears.

What I claim as new and desire to secure by Letters Patent of the United States is:

1. The combination with a switch box having 10 a plurality of walls, of a plurality of ears movable relatively to one another and rotatably pivoted to one of said walls, means for aligning said ears when they are rotated to one position to form a composite supporting member for the box and other means for aligning said ears when they are rotated to another position to form a similar composite supporting member for the box.
2. The combination with a switch box having 20 a plurality of walls, of a plurality of ears movable relatively to one another and rotatably pivoted to one of said walls, means for aligning said ears to form a composite supporting member for the box when they are rotated to a position lying in the same plane as the upper edge 25 of said wall, and other means for aligning said ears to form a similar composite supporting member for the box when they are rotated to another position offset from the edge of said wall.
3. The combination with a switch box having 30 a plurality of walls, of a plurality of ears movable relatively to one another and rotatably pivoted to one of said walls, means for aligning said ears to form a composite supporting member when they are rotated to one position and other 35 means for aligning said ears to form a similar composite supporting member for the box when they are rotated to another position substantially 180° distant from the first position.
4. The combination with a switch box having 40 a plurality of walls, of a plurality of ears movable relatively to one another and rotatably pivoted to one of said walls, a first and a second set of arms on said ears, said first set of arms cooperating to align the ears when they are rotated to one position to form a composite supporting member for the box, and said second set of arms 45 cooperating to align the ears when they are rotated to another position to form a similar composite supporting member for the box.
5. The combination with a switch box having 50 a plurality of walls, of a plurality of ears movable relatively to one another and rotatably pivoted to one of said walls, a first and a second set 55 of arms on said ears, said first set of ears cooperating to align the ears when they are rotated to one position to form a composite supporting member for the box and said second set of arms cooperating to align the ears when 60 they are rotated counter to their first directions of rotation to another position to form a similar supporting member for the box.
6. The combination with a switch box having 65

a plurality of walls, of a plurality of ears movable relatively to one another and rotatably pivoted to one of said walls, a first and a second set of arms on said ears, said first set of ears cooperating to align the ears when they are rotated in opposite directions to one position to form a composite supporting member for the box, and said second set of arms cooperating to align the ears when they are rotated in the opposite direction to a second position substantially 180° distant from the first position to form a similar composite supporting member for the box.

7. The combination with a switch box having 80 an attaching lug projecting outwardly from one of its walls, a pair of ears movable relatively to each other and rotatably pivoted to said wall, means for aligning said ears when they are rotated to one position to form a composite supporting member for the box which encloses said lug, and other means for aligning said ears when they are rotated to another position to form a composite supporting member for the box provided with an opening opposite said lug.

8. The combination with a switch box having 85 an attaching lug projecting outwardly from one of its walls, a pair of ears movable relatively to each other and rotatably pivoted to said wall, means for aligning said ears when they are rotated to one position to form a composite supporting member for the box which encloses said lug, and other means for aligning said ears when they are rotated to another position 100 100 105 110 115 120 125 130 135 140 145 150

180° distant from the first position to form a composite supporting member for the box provided with an opening opposite said lug.

9. The combination with a switch box having an attaching lug projecting outwardly from one of its walls, a pair of ears movable relatively to each other and rotatably pivoted to said wall, means for aligning said ears when they are rotated to one position lying in the same plane as the outer edge of the box to form a composite supporting member for the box enclosing said lug and other means for aligning said ears when they are rotated to another position opposite from the other edge of the box to form a composite supporting member for the box provided with an opening below said lug.

10. The combination with a switch box having an attaching lug projecting outwardly from one of its walls, a pair of ears movable relatively to each other and rotatably pivoted to said wall, a first and a second set of arms on said ears, said first set of arms cooperating to align the ears when they are rotated to one position to form a composite supporting member for the box which encloses said lug, and said second set of arms cooperating to align said ears when they are rotated to another position to form a composite supporting member for the box provided with an opening opposite said lug.
